AEROSOL BOMB VALVE AND GUARD

William E. Davis and Blanton J. Whitmire, Kirkwood, Mo., assignors to Whitmire Research Laboratories, Inc., St. Louis, Mo., a corporation of Missouri

Application October 11, 1955, Serial No. 539,745

4 Claims. (Cl. 222—394)

This invention relates to so-called aerosol bombs.

Aerosol bombs from which insecticides and the like are dispensed are commonly made in small sizes, the most common size being a bomb which holds 12 ounces of liquid. These bombs have a total spray life of about five to ten minutes. They have customarily been provided with a valve mounted in a pan-like closure which fits into the open top of the bomb and is sealed therein. The valve has a hollow brass stem of small diameter projecting out of the closure and a plastic knob mounted on the stem and equipped with a small nozzle. The contents of the can are released by pushing down on the top of the knob, which depresses the stem and permits the liquid to be released through the stem, into the interior of the knob and out through the nozzle.

These valves have worked fairly satisfactorily with the small bombs. The brief duration of the spray period has made the problem of the refrigerating effect of the expansion of the liquid from the nozzle of the valve of little practical concern. The valve knob has been depressed for only a short length of time, so that, while it is uncomfortable, holding the valve knob down has not been a serious problem. Also the lightness of the bombs and their short working life has minimized the problem of damage to the valve stem and the internal workings of the valve.

It has been considered unfeasible to use the common commercial light-weight valve with large heavy-walled tanks, such, for example as a three pound bomb or tank which may have a spray life of thirty to forty-five minutes. This view was prompted by several considerations. The light-gauge metal closure was thought to be incompatible with the relatively heavy wall of the container. The thin stem projecting from the valve was considered too light and easily damaged to withstand the heavier, rougher and longer use to which such large bombs are subjected in the course of being exhausted; and the danger of frostbite to the finger pushing down on the knob of the light-weight valve, when the spray period is prolonged, is serious. In addition, it is tiring to hold down the small knob for an extended period of time.

As a result of this thinking in the trade, heavy, large, expensive, screw-on type valves have been used with large sized bombs.

Accordingly, one of the objects of this invention is to provide a device by means of which a common commercial light-weight valve can successfully be used in a large aerosol bomb.

Another object is to provide a device which may be used in connection with a common commercial light-weight valve on any sized aerosol bomb, which device protects the valve against damage, protects the user of the bomb against frostbite, and provides easier operation of the valve.

Other objects will become apparent to those skilled in the art in the light of the following description and accompanying drawing.

In accordance with this invention, generally stated, a

2

device is provided with legs which fit slideably but snugly against the side wall of the cupped closure of a light-weight aerosol valve. The construction of the legs is such that the device protects the valve stem from injury and prevents undue side-thrust against the valve stem during use. The device includes a part, supported by the legs, which prevents the finger of the user from being frost-bitten, by keeping the finger out of the stream of spray immediately as it leaves the nozzle, and a part forming a broad bearing surface for the finger of the user. A clamping part of the device holds the valve knob against inordinate sideways movement or cocking and keeps the spray nozzle properly oriented.

The device is referred to hereafter as a guard. It is to be understood, however, that the term "guard" as used in describing the device is not used in the limited sense that the term might imply. The device of this invention serves not only to guard the stem against injury and the finger of the user against frostbite, but as a guide for the knob, a platform for the finger and therefore, in a sense, as a control device, as an ornament, and as a means for quickly indicating the orientation of the nozzle.

In the drawing,

Figure 1 is a plan view of a heavy-walled aerosol bomb provided with a light-weight aerosol valve equipped with a guard constructed in accordance with one embodiment of this invention;

Figure 2 is a fragmentary view in front elevation of the container showing the valve equipped with the guard shown in Figure 1;

Figure 3 is a fragmentary view in side elevation of the container, valve and guard shown in Figure 2;

Figure 4 is a fragmentary sectional view taken along the line 4—4 of Figure 1;

Figure 5 is a view in perspective of the guard shown in Figures 1 through 4; and

Figure 6 is a view in perspective of the guard shown in Figure 5 in inverted position.

Referring now to the drawing for an illustrative embodiment of this invention, reference numeral 1 indicates an aerosol bomb which, in the embodiment shown, is of a large (e. g., three pound) size, as indicated by the thickness of its wall 2 as shown in Figure 4. The bomb 1 has an opening 3 in its upper end, defined by a lip 4.

45 A light-weight valve 10 is seated in the opening 3. The valve 10 has a skirt 11 forming a pan-shaped closure for the bomb, with a rim 12 crimped over the lip 4 of the container 2 and an outwardly flaring annular bulge 14 around the inside and immediately below the lip 4 so as to seal the closure 11 in the opening 3. The bottom of the closure 11 is drawn upwardly to form an inverted cup 16 integral with the bottom. The cup 16 has a hole in its inverted bottom through which a stem 20 extends. The stem 20 is hollow and is usually made of brass. The cup

50 16 has an annular knurl 18 which serves to secure a valve housing 21 within the cup. A gasket 22 held against the inverted bottom of the cup by the housing 21 is adapted to seal an orifice in the wall of the stem 20 when the stem is in its uppermost position, and to be bent downwardly by a sloping shoulder 23 on the stem 20 when the valve stem is depressed. The stem is biased toward an upward position by a spring 24.

55 A knob or button 30 is mounted on the upper end of the stem 20. The knob 30 has a vertical passage connecting with the interior of the hollow stem 20, and a horizontal passage connecting with the vertical passage, and opening into a nozzle 34.

The valve which has been described is a common commercial light-weight aerosol valve and its construction, per se, does not form a part of this invention.

It can be seen that the stem 20, which in practice has an outside diameter of only about one-eighth of an inch

at its largest section, is liable to be damaged by side thrust, and that the internal workings of the valve are also liable to damage from that cause. It can also be seen that since the center of the nozzle 34 is only about one-eighth of an inch below the top-most part of the knob, there is serious danger of the operator's getting his finger at least partly over the nozzle opening. In an effort to indicate the direction in which the nozzle is pointing, and to inhibit the tendency to drape the operator's finger over the nozzle, the top surface of the knob has been cut at an angle sloping downwardly away from the nozzle. This has made the knob more difficult to push down and has tended to push the valve stem forward.

In the illustrative embodiment of this invention shown in the drawing, a guard 50 is provided. The guard 50, in this embodiment, is made of a single blank of metal. The guard 50 has three legs, a back leg 52 and two front legs 53. The legs 52 and 53 carry a platform 55. The platform 55 is made up of a rear section 56, a center section 57 and a front section 58. A pair of clamps 60 depend from the center section 57. A beak 62 projects from the forward edge of the front section 58.

The front legs 53 are integral with and connected to opposite sides of the front section 58 so as to leave a clear space between them over which the beak 62 projects. The back leg 52 is integral with and connected to the center of the rearward edge of the back section 56. The legs 52 and 53 are curved transversely on a radius substantially the same as the radius of the inside surface of the side walls of the closure 11.

The legs are so spaced with respect to one another that they slideably but snugly engage the inside surface of the side wall of the closure 11. The legs are of substantially the same length as the distance from the upper side of the bottom of the closure 11 to the top-most point of the knob 30 when the knob is in its fully depressed position.

The clamps 60 are integral with and connected to opposite sides of the center section 57. They are curved on a radius substantially the same as the radius of the outside surface of the knob 30, and are so spaced as snugly to engage the knob 30. They are so aligned that the space between them is centered with respect to the space between the front legs 53. The guard 50 can be installed either by positioning it directly over a valve upon which the knob has already been mounted and pushing the guard down so that the clamps 60 embrace the sides of the knob with the nozzle 34 pointing through the space between the clamps 60 toward the opening between the legs 53, i. e., in the direction indicated by the beak 62; or the knob can be demounted from the stem 20, pushed into position between the clamps 60, with its nozzle pointing in the direction of the beak 62, and the guard and knob pushed down over the stem. In either event, the legs 52 and 53 slideably engage the side wall of the closure 11.

In use, it is only necessary to push down on the relatively broad area of the platform 55 to depress the knob and stem. The front section 58 and the beak 62 positively and invariably prevent the finger of the user from getting into the stream of spray immediately as it issues from the nozzle, and therefore effectively prevent frostbite. The broad surface of the platform 55 provides a comfortable and effective bearing surface for the finger.

The legs 52 and 53 are close enough to the bottom of the closure 11 so that the stem 20 cannot be bent to the point at which damage can be done to it or to the internal workings of the valve. There is a certain amount of play allowed the stem by virtue of the spring and flexible gasket within the valve housing so that the legs 52 and 53 are entirely effective. It can be seen also that as the valve stem is depressed, the legs approach the bottom of the closure so that if, in use, there is a tendency to exert a side thrust on the valve stem, that tendency is completely overcome as the legs reach the bottom. A

straight side thrust, as from a blow in handling, will be taken by the legs.

The beak 62 performs three functions. It extends the front section of the platform, it serves to remind the user, because of its sharp point, to keep his finger back, and it indicates the direction in which the spray will issue.

The clamps 60 not only serve to keep the knob 30 centered and prevent sideways displacement of the knob, but ensure that the downward force exerted by the finger does not, as the beveled top of the knob tends to, cock the knob and valve stem forward. The clamps 60 also ensure that the nozzle is properly oriented and maintained in its proper orientation with respect to the front legs 53.

It has been found in practice that when the guard of this invention is used, heavy-walled three pound bombs can be equipped with ordinary light-weight valves, and the entire contents discharged under the same conditions of rough handling and use as the elaborate and heavy valves heretofore commonly employed, with no difficulty whatsoever.

Numerous variations in the details of construction of the guard of this invention, within the scope of the appended claims, will occur to those skilled in the art in the light of the foregoing disclosure.

Having thus described the invention, what is claimed and desired to be secured by Letters Patent is:

1. A valve guard on a pressure type container having a valve with a skirt providing a pan-shaped closure for the container, said closure having a bottom and a side wall with an exposed inner surface above said bottom, said valve having a vertically depressible hollow stem projecting above said bottom and a knob mounted on the upper end of said stem and carrying a nozzle, said guard comprising legs slideably engaging the inner surface of the side wall of the closure for axial movement with respect to the container, said legs being substantially as long as the distance from the top of said knob to the bottom of said closure when the stem is fully depressed and said legs being spaced apart to define an open space between them; a platform carried by said legs, said platform having a central section, and a clamp depending from said central section and embracing said knob, said clamp having an opening into which the nozzle of the knob extends, said clamp opening being aligned with the space between the legs, said platform extending above and beyond said knob and said nozzle.

2. The combination of claim 1 wherein the platform of the guard is provided with a pointed beak extending above the space between the legs and in a direction away from the nozzle of the knob.

3. The combination of claim 1 wherein the platform has a front section to opposite sides of which two front legs are integrally connected, a center section, to opposite sides of which a pair of clamping members forming the clamp are integrally connected, and a back section to which a back leg is integrally connected, said two front legs being spaced to define the opening with which the clamp's opening is aligned.

4. A heavy-walled cylindrical aerosol bomb having a valve with a skirt providing a pan-shaped closure for an opening in the upper end of said bomb, said closure being constructed of light gauge metal as compared with the wall of the bomb, said closure having a bottom and a side wall having an exposed inside surface above said bottom, said valve having a vertically depressible hollow stem and a knob mounted on said stem and carrying a nozzle, and a guard for said valve, said guard comprising legs slideably engaging the inner surface of the side wall of the closure for axial movement with respect to the bomb, said legs being substantially as long as the distance from the top of said knob to the bottom of said closure when the stem is fully depressed and spaced apart to define an open space between them; a platform carried by said legs, and a clamp depending

from a central section of said platform and embracing said knob, said clamp having an opening into which the nozzle of the knob extends, said opening being aligned with the space between the legs, said platform extending above and beyond said knob and said nozzle.
